DESIGN FOR A BILLFOLD OR THE LIKE

Berel A. Arnold, Boston, Mass., assignor, by mesne assignments, to Debonair, Inc., Boston, Mass., a corporation of Massachusetts

Application January 22, 1947, Serial No. 136,309

Term of patent 7 years

(Cl. D87—3)

To all whom it may concern:

Be it known that I, Berel A. Arnold, a citizen of the United States, residing in Boston, in the county of Suffolk and State of Massachusetts, have invented a new, original, and ornamental Design for Billfolds or the like, of which the following is a specification, reference being had to the accompanying drawing, forming a part thereof, in which the figure shows the inner side of a billfold showing my new design. The back of the billfold is plain and the dominant feature of the design is the lacing and its diagonal position as shown.

I claim:

The ornamental design for a billfold or the like, as shown and described.

BEREL A. ARNOLD.
